Original design application Nov. 10, 1972, Ser. No. 305,325. Divided and this application Jan. 22, 1974, Ser. No. 435,572

Term of patent 14 years

Int. Cl. D8—09
U.S. Cl. D8—179

FIG. 1 is a side view of an escutcheon plate incorporating my new design and shown as adapted for supporting a handle.

FIG. 2 is a front view of the plate taken along the line 2—2 in FIG. 1.

FIG. 3 is a bottom view of the plate.

FIG. 4 is a fragmentary sectional view taken along the line 4—4 in FIG. 2.

FIG. 5 is a sectional view taken along the line 5—5 in FIG. 2.

The portions shown in broken lines form no part of the design.

This application is a division of my co-pending application Ser. No. 305,325, filed Nov. 10, 1972.

I claim:

The ornamental design for an escutcheon plate, as shown and described.
